UNITED STATES PATENT OFFICE.

JOHN F. GILCHRIST, OF CHICAGO, ILLINOIS, ASSIGNOR TO FEDERAL ELECTRIC COMPANY, OF CHICAGO, ILLINOIS, A CORPORATION OF ILLINOIS.

COMBINATION WASHING MACHINE AND TABLE.

Application filed October 27, 1921. Serial No. 510,938.

To all whom it may concern:

Be it known that I, JOHN F. GILCHRIST, a citizen of the United States, and a resident of Chicago, county of Cook, and State of Illinois, have invented certain novel and Improved Combination Washing Machines and Tables; and I do hereby declare that the following is a full, clear, and exact description thereof, reference being had to the accompanying drawings, and to the letters of reference marked thereon, which form a part of this specification.

This invention relates to a novel combined washing machine and table and consists of the matters hereinafter described and more particularly pointed out in the appended claims.

It has been found that in a great many cases, as in apartment buildings and small houses, a washing machine is located and operated in the kitchen, rather than in a separate room used for laundry purposes only. In such instances, the washing machine, when not in use, is pushed aside against the wall or in a corner and is a useless incumbrance and which is much in the road during the greater part of the week.

The object of the invention is to provide an attachment for the washing machine body, namely a table top, which may be attached to the washing machine body, when it is not being used for purposes of washing, so that the washing machine may be used as a kitchen table, thereby doing away with the necessity for that useful and necessary article of kitchen furniture. Thus the washing machine is in effect made to disappear and to be replaced by a kitchen table, except during the comparatively short time in the week, when it is functioning as a washing machine.

The advantages of my invention will appear as I proceed with my specification.

In the drawings:—

Figure 1 is a perspective view of my combination washing machine and table, as it appears when in use as a table;

Figure 2 is a perspective view of the table top, detached from the washing machine bottom and faced bottom up;

Figure 3 is a view representing a side elevation of the upper part of the washing machine body with the table top attached thereto, shown in longitudinal section.

Referring now to that embodiment of the

invention illustrated in the drawings:—10 indicates the washing machine body which as shown is rectangular and which has upright supporting legs 11 at or near its four corners. The washing machine may be the usual power machine with a swinging wringer, shown in dotted lines at 12 in Figure 1, mounted to swing about a vertical axis on a boss 13 in a familiar manner. The washing machine body may if desired be made of sheet metal and has a hinged cover or top 14, which is hinged at one end to the one end edge of the open top of the body, with its other end extending towards but stopping short of the boss 13 and of the usual drip board 15 located below the space occupied by the wringer. Said cover closes at its sides on top of the side edges of the open top of the body. The hinge connection of the cover presents a narrow, generally rounded flange 14^a along the top of the washing machine body when the cover is closed.

The wringer 12 is removable from the boss 13 as usual, but in addition, the wringer is so connected to the gearing contained in the washing machine body below the boss 13, that when the wringer is removed, nothing remains to extend above the boss 13, which itself generally stands somewhat above the top of the washing machine body and its cover.

16 indicates a table top. This is preferably made of enameled sheet metal and is provided at its margins with depending flanges 18, 18^a which strengthen and finish the top. The top is made longer than it is wide, its width preferably being just sufficient so that the flanges 18^a, 18 at its sides embrace the sides of the open top of the washing machine body. The top is preferably made long enough to extend at each end somewhat beyond the ends of the washing machine body. Made in these proportions with reference to a washing machine of the usual kind as shown, the table top will approximate the dimensions of the usual kitchen table.

Blocks 19, 19 are attached to the bottom of the table top near one end and at equal distances from that end. As shown, and by preference, these blocks are attached by screws to the inside faces of the side flanges 18^a. Each block is provided at its inner end with a projection 20 which presents a

downwardly facing shoulder 21 at a level somewhat below the bottom face of the table top, adapted to bear upon the top of the washing machine near the margin of its 5 hinged end. Said block also has a recess 22 below the shoulder 21, which recess is adapted to engage the flange 14^a formed by the hinge of the cover when the inner end of the bottom of the block is brought against 10 the upright end wall of the body adjacent said flange. The projection 20 is of such thickness that the table top will be supported by it at a distance above the cover 14 equal to the distance that the boss 13 rises 15 above the level of said cover.

Near the other end of the table top, and secured, as shown, to its side flanges 18^a are located a second pair of blocks 23, 23, which are opposed to the first pair, and are spaced 20 therefrom a distance slightly greater than the length of the washing machine body. Said blocks each have a depending ear 24 through which is threaded a horizontal adjusting bolt or screw 25 with a butterfly 25 head,—said bolts extending towards the first named pair of blocks 19, 19.

To apply the table top 16 to the washing machine body, it is placed thereon (the cover of the washing machine first having 30 been closed) with its side flanges 18^a, 18^a embracing the sides of the washing body at the top and with the projections 21 of the blocks 19, 19 and the recesses 22 of said blocks 19 engaged on the cover 14 and on 35 the flange 14^a respectively as described. The other end of the table top is then lowered until it comes to bear upon the top of the boss 13, whereupon the adjusting bolts 25 are screwed into engagement with the end 40 wall of the washing machine body,—thus securely locking the table top in position. The ends of the bolts 25 will, in use, soon provide seats for themselves in the wall of the washing machine body so as to resist any 45 displacement due to a load on the table top. The blocks 23 may be provided, however, with projections 23^a, which extend toward the other pair of blocks and which present horizontal shoulders 23^b for bearing en-

gagement with the top edge of the washing machine body, as shown in Fig. 3. Such shoulders, together with the like shoulders on the blocks 19, 19, insure a horizontal, level position for the table top.

When the washing machine is to be used 55 as such, the table top may be readily and quickly detached by loosening the bolts 25 and disengaging the blocks 19, 19 from the flange 14^a, after which it may be set to one side on its edge against a wall, where it will 60 be entirely out of the road and ready for replacement and use when the washing is done.

I claim as my invention:—

1. A table top adapted for detachable engagement upon a support, said table top comprising a flat plate with depending side and end flanges, pairs of opposing blocks attached to the inner faces of said side flanges at points spaced to span the top of said support, one pair of blocks being provided with recesses for detachable engagement with a fixed part at one end of the support, and adjusting screws to engage said support carried by the other pair of blocks. 75

2. A table top adapted for detachable engagement upon a support, comprising a table top member, a pair of blocks carried on the under side of said top member near one end thereof and having recesses for detachable engagement with a fixed part of one end of said support, a second pair of blocks carried on the underside of said top member near the opposite end thereof, and means carried by said second pair of blocks and capable of manipulation to be engaged with and disengaged from said support and to coact with the first mentioned pair of blocks to detachably lock the top member to said support. 90

In testimony that I claim the foregoing as my invention, I affix my signature, this 20th day of October, A. D. 1921.

JOHN F. GILCHRIST.
